Des. 233,786
Patented Nov. 26, 1974

233,786

RADIUS OF CURVATURE MEASURING INSTRUMENT

Donald L. Woodford, 1114 S. 98th St.,
Omaha, Nebr. 68124

Filed Feb. 7, 1973, Ser. No. 330,425

Term of patent 14 years

Int. Cl. D10—04
U.S. Cl. D52—6 R

FIG. 1

FIG. 2

FIG. 3

FIG. 4

FIG. 1 is a front isometric view of a radius of curvature measuring instrument showing my new design;

FIG. 2 is a front elevational view thereof;

FIG. 3 is a right side elevational view thereof, the left side being substantially a mirror image thereto;

FIG. 4 is a top plan view thereof.

I claim:

The ornamental design for a radius of curvature measuring instrument, substantially as shown and described.
